Frank M. Ashley
ATTORNEY

UNITED STATES PATENT OFFICE

WALTER S. EDGE, OF WESTFIELD, NEW JERSEY

METAL ROD FOR BUILDING CONSTRUCTION, ETC.

Application filed March 6, 1928. Serial No. 259,396.

My invention relates to metal rods and their use.

The object of my invention is to provide metal rods and especially iron rods of small and medium diameters at a low cost and with at least one surface extending longitudinally of each rod or set of rods, that presents the raw metal of the rod or set, when the same are finished while leaving the remaining surfaces coated with the thin scale with which they are covered when they leave the rolls which form them.

My invention will be more clearly understood by referring to the drawings which form a part of this specification in which—

Figure 1 is a cross sectional view of a sheet of iron embodying a plurality of circular portions, which become separate rods when the sheet is divided midway between the said circular portions by a slitter or saw.

Figure 2 is a similar view to that shown in Figure 1, including a gang of slitters for separating the rods.

Figure 3 is a cross section of a finished rod embodying my invention.

Figure 4 is a perspective view of a number of rods, illustrating an arrangement whereby the raw surfaces are brought into contact for welding them together.

Figure 5 is a view showing one rod welded to another, the rods being arranged at a right angle to each other.

Figure 6 is a cross sectional view of a set of hexagonal rods, as formed prior to separating them into single rods.

The rods may be formed with any desired cross section, and made into single, double, or any predetermined number, as desired, by simply cutting through the web of the sheet.

In the following description I shall refer to two or more rods joined by a web or web portions, as a set of rods.

A, A, etc. indicate the body portions of the rods and B, B, etc. the web portions formed integral with the body portions.

C, C, etc., indicate the raw metal surfaces provided by separating the rods with saws or slitting tools to provide a single rod

as illustrated in Figure 3, having a web on each side thereof, each of which is provided with a raw surface C, which extends the full length of the rod, while leaving the remaining surface in the normal condition in which it leaves the rolls.

D, D, D, etc., indicate the saws.

It is obvious that a web may be formed on one side of the rod only by sawing through the sheet directly adjacent the body of the rod on one side, thus leaving a web on the opposite side only. The advantages of this construction are; first, the rod is stronger and stiffer by reason of the web portions; second, the raw surfaces permit of easy spot welding, and third; they are less costly to make by reason of a number being rolled simultaneously.

Where concrete is to be re-inforced by rods, as in buildings and dam constructions, etc., I may use a set of rods in place of single rods in many cases and reduce the cross sections in size in many instances, thus saving in weight of metal and at a lower cost.

I am aware that rods have been rolled or formed by rolling in sheets to provide separate rods at a low cost, but I believe it is new to provide rods with webs as above set forth and with webs having a plane raw surface extending their entire length and provided by the process of making as above set forth, and therefore believe both the process and product to be new and useful.

Having thus described my invention I claim as new and desire to secure by Letters Patent:

1. A metal rod of the character described having a web formed integral therewith extending its entire length and having one side of said web provided with a plane surface exposing the raw metal resulting from a sawing or shearing operation.

2. A metal rod of the character described having a web formed integral therewith extending its entire length on opposite sides thereof, each web having a plane surface exposing the raw metal resulting from a sawing or shearing operation.

3. A rolled metal rod of the character

described having a web formed integral therewith extending longitudinally thereof its entire length, the outer face of the web exposing the raw metal resulting from a sawing or shearing action and the remaining portion being covered by its outer normal covering as it leaves the rolls which form it.

4. A rolled metal rod of the character
10 described having web portions formed diametrically opposite to each other and extending the entire length thereof and having their outer faces formed with plane surfaces exposing the raw metal resulting from
15 a sawing or shearing action.

In testimony whereof I have affixed my signature.

WALTER S. EDGE.
